David Beard
Gallows Patent

The Schedule referred to in these Gallows Patent and
making part of the same containing a description in the words
of the said David Beard himself of his improvement in
Spherical Gallows Fur Cutting Machine. —

— Description of the Improvement —

First the master wheel $\frac{1}{2}$ the wheel on the shear shaft
 $\frac{3}{4}$ the wheel on the feeding rollers the master wheel is one
third larger; the wheel on the shear shaft $\frac{2}{3}$ larger, and the
wheel on the feeding roller 2 inches larger in diameter
than the original machine, all so constructed as to work
with a peddall by the foot instead of the hand. Also a
Slider is fixed to move between the feeding rollers and the
steel blade with a trigger to the left hand post, to push
the skin up, if it should incline down; also moving the
top feeding roller in from the centre towards the shear blades
as far as it will bear, so as for the shear to miss it, which
prevents the skin from raising too high. The improvement
on the other end of the Bench is calculated to even the
fur skin of the hair by two sets of rollers, one set of wood &
the other of steel. The top steel roller has a number of fur-
rows cut lengthways in it, both pairs of these rollers run
in frames made of iron, which frames are confined together
by screws. The steel rollers are set on sliding plates of
iron to slide within the frames above mentioned and governed
by screws so as to set them nearer or further off from the
wood rollers to suit the different lengths of fur. The
steel rollers are set behind the wooden rollers and are
set higher, so that the contact of the steel rollers shall be
horizontally against the middle of the top wooden rollers.
The skin is put in between the wooden rollers last foremost

and turned over the top roller, and a pair (for more if needed) of hair nippers calculated with springs to make them hold fast, to the edge of the skin, after it is turned over the top roller, the lower ends of the nippers are made hooked so as to hang weight thereon to hold the skin tight to the top roller, so that the steel rollers shall not pull fur nor skin with the hair. Both pair of the aforementioned rollers may be worked, by bands running on the first mentioned master wheel with the needles by the foot or by cranks fixed to them as may be most convenient.
